UNITED STATES PATENT OFFICE.

CHARLES L. BRALEY, OF CINCINNATI, OHIO, ASSIGNOR TO THE AMERICAN LAUNDRY MACHINERY COMPANY, OF CINCINNATI, OHIO, A CORPORATION OF OHIO.

AIR-COMPRESSOR.

1,272,611.

Specification of Letters Patent. Patented July 16, 1918.

Application filed September 9, 1916. Serial No. 119,289.

To all whom it may concern:

Be it known that I, CHARLES L. BRALEY, a citizen of the United States, residing at Cincinnati, in the county of Hamilton and State of Ohio, have invented certain new and useful Improvements in Air-Compressors, of which the following is a specification.

This invention relates to air compressors. The object of the invention is to provide an automatic air compressor of simple form having a large capacity for its size and provided with improved cooling mechanism. A further object of the invention is to provide an air compressor suitable for a wide variety of uses, which is wholly self-contained, and which embodies in a unit structure all the parts necessary to create and maintain a supply of compressed air at any desired pressure without attention by the operator.

Further objects of the invention are in part obvious and in part will appear more in detail hereinafter.

The invention comprises the air compressor hereinafter described and claimed.

In the drawings, which represent one embodiment of the invention, Figure 1 is an elevation, partly broken out and in section to show the interior mechanism; Fig. 2 is a sectional elevation on the line 2—2, Fig. 1; Fig. 3 is a plan view; Fig. 4 is an elevation, partly broken out and in section, of a motor controlling switch; Fig. 5 is a bottom plan view thereof; and Fig. 6 is a detail view, corresponding to Fig. 2 and on a larger scale, of an air valve.

The air compressor shown in the drawings comprises a suitable body or base, shown as a hollow metal casting 1 provided with slotted or perforated ears 2 for attachment to any suitable support. In said base is a large chamber 3 forming a storage reservoir for the compressed air. The base may be of any suitable shape but, as shown in the drawings, is rectangular in plan view and in one corner is provided with an inner wall 4, which, together with the outer wall 5, forms a hollow jacket within which is located the compressor cylinder 6, which is a separate member having its lower end reduced, as at 7, and threaded into the bottom of the jacket. In the lower end of the cylinder is an air inlet valve shown in detail in

Fig. 6 and comprising a valve member 8 seating outwardly from the chamber 3 and having a stem 9 sliding in a central opening in a spider 10 threaded into the cylinder casting, said valve being held to its seat by a compression spring 11 located between the spider 10 and valve member. In the cylinder chamber 12 is a pump piston 13, comprising a solid body having upwardly extending ears 14 to receive a pivot pin 15 connecting said piston to the connecting rod 16. The piston is also provided with an air valve, comprising a valve member 17 seating outwardly from the cylinder chamber and having a longitudinally grooved stem 18 sliding in a longitudinal opening of the piston, said opening communicating with the atmosphere on the outer face of the piston. The valve stem is provided at its outer end with a head 19 and is held to its seat by a compression spring 20 located between the outer face of the piston and the head 19.

The casing or body 1 of the compressor is provided with an upwardly extending portion 21 which not only increases the capacity of the reservoir 3, but whose walls form a support for the operating mechanism. The compressor is driven in any suitable manner, such as by an electric motor 22 fastened to the casing, and whose shaft is coupled to a driving shaft 23 journaled in the casing extension 21, said shaft being provided with a worm 24 driving a worm gear 25 on a transverse shaft 26 whose outer end is provided with an eccentric pin 27 for operating the connecting rod 16 to reciprocate the pump piston in its cylinder. The worm and worm gear described are preferably inclosed by a cover 28, which protects the gearing and prevents accidents.

Between the outer surface of the pump cylinder and the surrounding jacket 4, 5 is a hollow space which is utilized for cooling the pump by circulating air therethrough. As shown, this space is divided into one or more helically disposed passages 29 by a helical rib or vane 30, which may be integral with or secured either to the jacket, 4, 5 or the cylinder 6 and is shown as an integral part of the cylinder. The helical rib assists in conducting the heat away from the cylinder and radiating it to the air circulated through the helical passage 29. The outer end of the rib 30 terminates in a cir-

cular plate which covers the chamber around the piston but which plate is provided with a series of openings 31 through which air is discharged from the cooling passages to the atmosphere. The other end of the cooling passage, at the lower end of the cylinder, communicates with an air inlet 32 at one end of a conduit 33 communicating with a suitable air pump 34 opening at 35 to the atmosphere. Said air pump may be of any suitable type, such as a fan or blower, and its shaft 36 is driven by the same motor that operates the compressor, being provided with a gear 37 driven by a gear 38 on the worm shaft 23.

Preferably, suitable means is provided for automatically controlling the pump operating device, such as the electric motor, so as to automatically maintain any desired degree of pressure in the reservoir without special attention by the operator. As shown, the leads 39 of the motor circuit are connected to an electric switch shown in detail in Figs. 4 and 5. Said switch comprises a block 25 or body 40 of insulating material in which are embedded two contact members 41 having terminal screws 42 to which the leads are connected. Said body is also provided with a longitudinal opening 43 to receive a conducting sleeve 44, which is frictionally held, pinned or otherwise secured to move with an operating rod 45 slidably mounted in said bore and normally held in the position shown in Fig. 4 by a compression spring 46. In this position the conducting sleeve 44 bridges the gap between the two contact members 41 and closes the motor circuit, so that the pump is operating. When the conducting sleeve is moved upwardly, the circuit across the conducting members 41 is broken and the motor stops. The operating rod 45 is lifted automatically by the pressure in the reservoir 3 which, at one side, communicates with a port 47 leading to the under face of a small piston 48 sliding in a chamber 49 of a larger diameter than the port 47 and attached to a stem 50 sliding in a guiding plug 51 threaded into the casing and which stem extends above said plug and lies just below the operating rod 45, as shown in Fig. 2. The piston 48 is held to its seat at the bottom of the chamber 49, as shown in Fig. 2, by a compression spring 52, and in said position the stem 50 is out of contact with the operating rod 45 and the electric switch is closed. When the pressure in chamber 3 reaches the desired maximum it is sufficient to lift the piston 48 from its seat against the pressure of spring 52, and as soon as said piston 60 rises from its seat, the pressure in the reservoir becomes effective over the entire or larger bottom area of the piston, and therefore snaps the piston upwardly with sufficient force to raise the operating rod 45 and open the motor switch. The piston 48 will

remain in its upper position, with the motor switch open, until the pressure in the reservoir 3 drops to the minimum, whereupon spring 52 returns the piston to its seat and allows the motor switch to close. The plug 51 serves as an adjustment for the pressure to be maintained in the reservoir. By screwing said plug inwardly the tension of the spring 52 is increased and a greater pressure is required to lift the piston and open the switch. The plug 51 may be held in its adjusted position in any suitable manner, as by the set screw 53.

The compressor described is of simple form and is designed to maintain any desired degree of compression in its reservoir without attention by the operator. It has a large capacity for its size and has maximum efficiency due to the cooling arrangement described. By circulating air around the cylinder heat is radiated rapidly to the atmosphere and the piston is not liable to bind in the cylinder.

The compressor may be used for any desired purpose, but is adapted more particularly for operating small machines driven or controlled by compressed air. By utilizing one compressor for operating one or two of said machines efficiency is increased by doing away with the considerable loss of air entailed when a large number of machines are driven by air pressure supplied through a pipe line from a single large compressor.

What I claim is:—

1. An air compressor, comprising a cylinder having a hollow wall provided with a passage therethrough open to the atmosphere at one end, motor means, a piston driven thereby and operating in said cylinder, means operated by said motor means for circulating air through said passage to the atmosphere, and means for supplying air to said cylinder directly from the atmosphere.

2. An air compressor, comprising a cylinder having a hollow wall provided with a tortuous passage therethrough open at one end to the atmosphere, a valve in one end of said cylinder, a piston, a valve therein, means for reciprocating said piston, and means for circulating air through said passage to the atmosphere.

3. An air compressor, comprising a cylinder having a hollow wall provided with a tortuous passage therethrough open at one end to the atmosphere, a valve in one end of said cylinder, a piston, a valve therein, means for reciprocating said piston, and an air pump operated by said piston reciprocating means for circulating air through said passage to the atmosphere.

4. An air compressor, comprising a cylinder having a hollow wall forming a cooling space, a helical rib or vane in said space forming a helical passage therethrough, said

- passage at one end being open to the atmosphere, a piston working in said cylinder, and means for circulating air through said passage to the atmosphere.
5. An air compressor, comprising a casing forming a reservoir for air, part of said casing being formed to provide a jacket, a cylinder inclosed within said jacket and spaced therefrom, a valve controlling the flow of air from said cylinder to said reservoir, a piston working in said cylinder, and means for circulating air through the space between said cylinder and jacket.
6. An air compressor, comprising a casing forming a reservoir for air and provided with an inner wall forming a jacket, a cylinder inclosed in said jacket and spaced therefrom, a helical rib or vane in the space between said cylinder and jacket forming a helical passage therebetween, said passage at one end being open to the atmosphere, a piston working in said cylinder, and means for circulating air through said passage to the atmosphere.
7. An air compressor, comprising a hollow casing forming a reservoir for air, a pump for supplying air to said reservoir, a motor operating said pump, a fan driven by said motor for circulating cooling air around said pump, a switch controlling said motor, and a piston subject on one side to the pressure in said reservoir and arranged when
- 35 said pressure reaches a maximum to move outwardly and open said switch.
8. An air compressor, comprising a hollow casing forming a reservoir for air, a pump for supplying air to said reservoir, a motor operating said pump, a fan driven by said motor for circulating cooling air around said pump, a switch controlling said motor, and a piston subject on one side to the pressure in said reservoir and on its opposite side to the pressure of a spring and arranged when said reservoir pressure reaches a maximum to move outwardly and open 40 said switch.
9. An air compressor, comprising a hollow casing forming a reservoir for air, a pump for supplying air to said reservoir, a motor operating said pump, a fan driven by said motor for circulating cooling air around said pump, a switch controlling said motor, a piston subject on one side to the pressure in said reservoir and on its opposite side to the pressure of a spring and arranged when 45 said reservoir pressure reaches a maximum to move outwardly and open said switch, and means for adjusting the pressure of said spring.

In testimony whereof I affix my signature. 50

CHARLES L. BRALEY.
